UNITED STATES PATENT OFFICE.

NORMAN E. PIERCE, OF CHICAGO, ILLINOIS.

BAG-HOLDER.

SPECIFICATION forming part of Letters Patent No. 669,660, dated March 12, 1901.

Application filed December 7, 1900. Serial No. 39,018. (No model.)

To all whom it may concern:

Be it known that I, NORMAN E. PIERCE, a citizen of the United States, residing at Chicago, in the county of Cook and State of Illinois, have invented a new and useful Bag-Holder, of which the following is a specification.

My invention relates to that class of devices intended for the support and distention of bags for filling, and has for its intention simplicity in structure and operation and economy in manufacture.

My invention will fully appear in the following description, reference being had to the annexed drawings.

In the drawings, Figure 1 presents a perspective view of my invention in operation. Fig. 2 is a detail view of the holding device. Fig. 3 is a side view of the holder, presenting the holding device in a horizontal plane. Fig. 4 is a variation of my invention, showing a means for aiding to hold gunny-sacks and other loosely-woven bags, presenting the cross-head in section.

More particularly described, I represent by letters the details of my invention as shown in the drawings.

A represents the base of the frame of my holder, which is constructed of any desirable flat sheet of timber or any other suitable rigid material. From the base A rises perpendicularly a standard B, of any rigid material. Secured to this standard B by means of the wire loop c, supported on said standard by the pin or screw b, is a cross-head C, of any suitable material, preferably wood. To this cross-head C is attached my holder proper, which consists of a single piece of stiff wire D, peculiarly formed to meet the demands of my invention and forming in general outline with the cross-head C a rectangle, of which the wire D forms three sides and the cross-head the fourth. This wire D is secured at either end to the cross-head C, as shown in Fig. 2. I show these ends secured by looping the ends d d and passing screws through the loops into the cross-head. I then extend the wire up the face of the cross-head and secure it thereto by staples d' d'. The wire from these secured ends extends upward perpendicularly to a point slightly above the upper edge of the cross-head C. Then it is bent

forward and formed into horizontal coils D' D'. The wire D is then bent forward and slightly downward, and loops D² D² are formed, 55 which extend inward and slightly upward from the horizontal plane of D' D'. The wire D is then continued forward and downward, and the coils D³ D³ are formed. These coils lie in the same plane with the coils D' D', and 60 the four coils D' D' and D³ D³ form the four corners of my rectangle. The wire after forming D³ D³ is then passed across parallel with the cross-head C to form the fourth side of the rectangle. On this fourth side the wire 65 D is formed into a coiled spring D⁴, which extends downward and approximately at right angles to the coils D' D' and D³ D³.

The operation of my device is as follows: The open end of the bag to be secured is 70 passed up through the holder and the corners of the open end folded outward over the four coils D' D' and D³ D³. The edges are then forced under the loops D² D², which serve to take up the slack in the bag and draw it tightly 75 and securely around the coils. If the bag be smaller than the holder in its normal position, by forcing the ends of the holder toward each other various sizes of bags may be held. In this bending the coiled spring D⁴ moves downward and permits of the bending without injury to the holder, which when released springs back to its normal position.

I show in Fig. 4 the ends of the wire d d, instead of being looped and secured, as shown 85 in Fig. 2, turned toward and driven through the cross-head C. These ends are left to protrude from the back side of the cross-head C and having sharpened ends d² d² may be used to hold gunny-sacks or other loosely-woven 90 bags, which are drawn upward through the holder and over the cross-head and fastened onto the sharpened ends d² d².

In order to accommodate bags of different lengths, as it is desirable that the bottom of 95 the bag should rest on the base A in order to prevent strain on the holder by the weight of the contents of the bag, the screw b may be a pin and a series of sockets arranged one above the other in the back of the standard B to regulate the height of the cross-head, or any other convenient regulation means may be employed.

When the bag is fitted on the holder, the

mouth is held open in a rectangular form, the forward side of the mouth lying lower than the rear side in order to present a more convenient opening for receiving grain or other substance with which the bag is to be filled.

The coils which I provide for the support of the bag give resiliency and at the same time strength and comparative rigidity to the device.

10. What I claim as my invention is—

1. A bag-holder consisting of a single piece of wire secured at its terminals to a cross-head and extending therefrom forward and downward, forming a rectangle and arranged with 15 a coil at each corner thereof, substantially as

described, and for the purposes herein set forth.

2. A bag-holder consisting of a single piece of wire secured at its terminals to a cross-head and extending therefrom forward and downward, forming with such cross-head a rectangle, with a coil at each corner and one or more intermediate loops and coiled springs, substantially as described, and for the purposes herein set forth. 20

NORMAN E. PIERCE.
